FUEL INJECTION SYSTEM

Donald E. Meitzler, Manchester, Conn., assignor
to United Aircraft Corporation, East Hartford,
Conn., a corporation of Delaware

Application January 28, 1944, Serial No. 520,068

9 Claims. (Cl. 103—154)

1

This invention relates to injection systems for internal combustion engines and particularly to the driving mechanism for the injection plunger.

Injection plungers are generally actuated by a cam acting on a roller mounted either directly on the injection plunger or on a thrust cup surrounding the plunger. Although the roller is satisfactory in many installations, it is frequently difficult to provide a large enough bearing surface between the cam and the roller especially if the pump is operating under high pressures. An object of this invention is to overcome this difficulty by using a bearing shoe between the driving member and the injection plunger.

It may be advantageous in some installations to have the injection pump actuated by an oscillating driving member. At high speeds, the inertia of the roller which rides on the driving member may prevent the roller from reversing at the end of the stroke of the driving member. As a result the roller slips on the driving member and wears rapidly. A feature of this invention is a rocking shoe bearing forming a part of the connection between the plunger and the oscillating driving member.

Other objects and advantages will be apparent from the specification and claims, and from the accompanying drawings which illustrate an embodiment of the invention.

The single figure is a sectional view through an injection plunger and the driving mechanism.

The casing 10 has a bore 12 in which is a plunger 14 shown in the position at which injection of fuel into the engine cylinder takes place. When the plunger is at the lower end of its stroke, it uncovers an inlet port 16 to admit fuel to the end of the bore. During the injection stroke, fuel is forced by plunger 14 into accumulator chambers 18 and 20 through a groove 22 in a valve 24 and a cross passage 26 connecting the accumulator chambers. Valve 24 is slideable in a bore in a ring 30 in the casing.

While fuel is being forced into the accumulator chambers, valve 24 closes a passage 32 which connects cross passage 26 with the discharge nozzle 34. One end of valve 24 is in line with a seat 36 at the end of passage 32 and is held on this seat by pressure of fuel on the other end of the valve during the injection stroke of the plunger. Groove 22 permits a throttled flow of fuel past valve 24 into the chambers. The end of valve 24 remote from seat 36 is conical to engage a seat 38 in ring 30.

Air in the accumulator chambers 18 and 20 may be vented through a passage 42 in casing 10

2

which connects with the end of chamber 18. The opposite end of the passage forms a port 44 in bore 12 which, during a part of the plunger stroke, is connected to a relief port 46 by an annular passage 48 formed by a reduced portion of the plunger.

Discharge of fuel through passage 32 to nozzle 34 may be controlled by a check valve 50 held against a seat by a spring 54. When accumulator valve 24 moves to open passage 32, fuel pressure opens the check valve 50 and fuel is discharged past the check valve until the pressure of spring 54 is greater than the pressure differential holding the valve open. The check valve may have an integral plunger 56 slideable in a bore 58 in nozzle 34, the plunger having a longitudinal groove 60 for flow of fuel past the plunger.

The plunger is actuated by a driving member, which, in the arrangement shown, is a cam 62 having an oscillatory motion about the axis of shaft 64. A rocking shoe 66 is carried on a pin 68 supported in lugs 70 on a thrust cup 72 surrounding, and reciprocating on, casing 10. The lower end of the plunger 14 engages the base of 25 the thrust cup and is held against the cup by a spring 74. Another spring 76, surrounding casing 10, urges the thrust cup downwardly, holding the rocking shoe against the cam.

Shoe 66 may be constructed so that the leading 30 edge, during the injection stroke, is farther from the line of thrust through the center of oscillation than is the trailing edge. In this way, the rocking shoe will assume a position to provide the most effective lubrication film between the 35 shoe and the cam. It will be apparent that during the upward stroke of the plunger, the high pressure developed in bore 12 places a much heavier load on the rocking shoe than is applied during the downward movement of the plunger.

As the cam oscillates, starting from the position shown, the cam first moves counter-clockwise permitting the plunger and thrust cup to move downwardly within the casing under the influence of springs 74 and 76 until the plunger 45 uncovers inlet port 16 so that the space at the head of the plunger is filled with fuel. The cam then moves clockwise and moves the plunger upwardly, closing inlet port 16 and also closing port 44. Fuel is pumped by the plunger through 50 groove 22 in valve 24 into the chambers 18 and 20, the valve at this time being held against the seat 36 by the pressure within bore 12. Continued plunger movement raises the pressure of the fuel in the accumulator chambers until port 55 16 in casing 10 is uncovered by annular passage

48 connected to the end of plunger 14 by a groove 80 in the plunger. The sudden drop in pressure at the end of the plunger when port 16 is uncovered causes valve 24 to move endwise to engage seat 38 and to open passage 32 for discharge of fuel from the accumulator chambers through the nozzle.

As the cam reverses at the start of the pumping stroke, rocking shoe 66 pivots on its support into the proper position for most effective lubrication between the shoe and the cam. For the part of the pumping stroke where the highest loads occur, which is just prior to uncovering of port 16 by groove 48, the curvature of the cam is approximately the same as that of the shoe to distribute the load over substantially the entire shoe surface. The rest of the cam may be non-eccentric to provide the desired plunger movement. Obviously, even though the cam has a smaller radius of curvature than the shoe, the latter will still function as a shoe bearing with the load distributed over a substantial part of the bearing area of the shoe.

The shoe is long enough to provide the necessary area of contact to carry the loads developed during the pumping stroke, but short enough to permit the shoe to rock to form the wedge-shaped oil film necessary for effective lubrication during the pumping stroke so that the load is distributed over substantially the entire shoe area, at least at the points where the highest loads occur.

An arrangement of this character may be of advantage in a free-piston unit of the type shown in the copending Kalitinsky application, Serial No. 486,611, filed May 11, 1943, patented Nov. 5, 1946, No. 2,410,448. In this type of unit the opposed free pistons may be caused to move symmetrically by a restraining linkage including racks projecting from the opposed pistons and meshing with a centrally located pinion. The pinion, which has an oscillatory movement, may be directly connected to cam 62 to procure injection in timed relation to piston reciprocation.

It is to be understood that the invention is not limited to the specific embodiment herein illustrated and described, but may be used in other ways without departure from its spirit as defined by the following claims.

I claim:

1. An injection pump including a plunger, a casing in which the plunger reciprocates, a non-circular cam for moving the plunger and a rocking bearing shoe connected to the plunger and engaging the cam, the part of said cam which engages the shoe during the portion of the injection stroke at which the highest pressures on the plunger develop having a substantially constant radius of curvature and the bearing surface of the shoe having substantially the same radius of curvature.

2. An injection pump including a plunger, a casing in which the plunger reciprocates, an oscillating cam for moving the plunger, and a pivoted rocking bearing shoe between said cam and the plunger and engaging said cam, said shoe having a short arcuate bearing surface engaging the cam.

3. An injection pump including a plunger, a casing in which the plunger reciprocates, an oscillating member for moving the plunger, and a rocking shoe between said member and the plunger, said shoe having its pivotal axis so located as to be forward of the center of the bearing surface of the shoe on the pumping stroke.

4. An injection pump including a plunger, a casing in which the plunger reciprocates, an oscillating member for moving the plunger, on the pumping stroke and a rocking shoe between said member and the plunger and engaging said member, said shoe being short enough so that the load is applied over substantially the entire shoe area.

5. An injection pump including a plunger, a casing in which the plunger reciprocates, a thrust cup engaging said plunger and guided by the casing, an oscillating member for moving the plunger and cup, and a rocking shoe on the cup engaging the member.

10 6. An injection pump including a plunger, a casing in which the plunger reciprocates, a thrust cup engaging said plunger and guided by the casing, an oscillating member for moving the plunger and cup, and a rocking shoe on the cup engaging the member, said shoe being small enough to cause the load to be distributed over substantially the entire area of the shoe.

15 7. An injection pump including a plunger, a casing in which the plunger reciprocates, a thrust cup engaging said plunger and guided by the casing, an oscillating cam for moving the plunger and cup, and a rocking shoe on the cup engaging the cam, the shoe engaging surface of said cam, for that part which is operative during the highest loads on the plunger, having a substantially constant radius of curvature.

20 8. An injection pump including a plunger, a casing in which the plunger reciprocates, a cam for moving the plunger, and a rocking bearing shoe between said plunger and cam and engaging said cam with sliding contact, said shoe having its pivotal axis so located as to be forward of the center of the bearing surface of the shoe on the pumping stroke.

25 9. An injection pump including a plunger, a casing in which the plunger reciprocates, a cam for moving the plunger, and a rocking bearing shoe between said plunger and cam and engaging said cam with sliding contact, the shoe-engaging surface of the cam having a varying radius of curvature, said shoe being short enough so that the load is applied over substantially the entire shoe area.

DONALD E. MEITZLER.
